CHILD'S NOVELTY HAND BAG

Max Tannenbaum, Brooklyn, N. Y.

Application April 6, 1935, Serial No. 15,024

3 Claims. (Cl. 46—46)

This invention relates to children's purses or hand bags and has particular reference to a child's novelty purse, bag or other similar container having a sound or voice producing device associated therewith which is actuated by compression of the walls of the purse, bag or other container.

The invention also comprehends a container of the type specified having flexible walls and a lining therefor, with a sound producing device located between one of the walls and the lining and adapted to be actuated by compression of either of the outer walls.

More particularly the invention resides in the combination with a child's purse, hand bag or equivalent container, including a pouch having a mouth formed with rigid pivotally connected frame jaws and flexible side walls, of a sound producing device including a hollow normally distended flexible body having a rigid sound tube disposed parallel with and adjacent to the frame jaws and the body located between the flexible side walls of the purse so that inward pressure on either of the side walls thereof actuates the sound producing device.

The invention also provides an improved sound producing device for use in an article having flexible walls, which device includes a sound tube and a hollow flexible air impervious body from which the tube extends, the said body being filled with matted, stranded inherently resilient material to normally distend the walls of the body and which, when compressed, will expand the body so as to effect the intake of air through the sound tube to thereby actuate the sound producing device.

The invention further includes a child's novelty container provided with a representation of an animal depicted on the outer surface thereof and with a sound producing device associated therewith and adapted to emit sounds simulating the voice of the animal depicted thereon.

With these and other objects in view, the invention is shown in the accompanying drawing in which there is illustrated a preferred form of the invention, while the appended claims cover variations and modifications thereof which fall within their scope.

In the drawing:

Fig. 1 is a face view of a child's purse embodying the container.

Fig. 2 is an enlarged vertical sectional view taken approximately on the line 2—2 of Fig. 1.

Fig. 3 is an enlarged fragmentary longitudinal

sectional view taken approximately on line 3—3 of Fig. 2.

Referring to the drawing by characters of reference, 10 designates the pouch or body of a child's purse, although within the scope of the invention any equivalent container or structure is intended to be covered, which includes opposed flexible side walls 11 and 12 with a pair of rigid frame jaws 13 and 14 secured to the open edge of the pouch. The frame jaws are pivotally connected as at 15 and as illustrated in the present disclosure, the pouch or body is provided with a flexible lining 16.

As shown, a sound producing device, which is designated generally by the reference character 17, is located within the pouch or body 10 between the opposed walls 11 and 12 so that compression of either of the side walls of the pouch will cause the functioning of said device 17. The device 17 includes a hollow flexible air impervious body 18 having a rigid sound tube 19 located at the upper portion of the body and having an open end protruding therefrom, the inner end being closed as at 20 with a reed 21 extending through the closed end of the sound tube and provided with a vibrating tongue 22 for creating a sound when air is drawn into the body through the sound tube and reed. The body 18 contains a matted, stranded inherently resilient material 23 which normally acts to distend the walls of the body and which, when compressed, contracts the body and expels the air therefrom, the subsequent inherent expansive action of the material 23 serving to distend the body to thereby effect the intake of air through the sound tube and reed to actuate the tongue 22 for creating the sound.

As illustrated, the sound producing device 17 is secured to the wall 12 at its corners by stitching 24 with the rigid sound tube and reed located adjacent or in close proximity to and parallel with the rigid frame jaw 14 so as to protect the tube and reed and position the same in the region of the pouch or body which is rendered rigid by the frame jaws so as to avoid distortion or breakage of the sound tube and reed. The remainder of the soft yieldable body portion of the sound producing device depends from the frame jaws where it is disposed in a position where it may be readily compressed by pressure exerted on either one or both of the side walls 11 and 12.

In order to conceal and protect the sound producing device and to prevent interference of the same with the contents of the purse, the sound producing device 17 is preferably located between one of the side walls 12 and the lining 16.

Preferably the pouch or body 10 will be decorated with representations of animals and the sound producing device will be constructed so as to emit sounds simulating the voice of the animal depicted thereon, so as to render the device more attractive and amusing to a child.

5 What is claimed is:

- 10 1. A child's hand bag including a pouch formed with flexible side walls, a pair of rigid pivotally connected frame jaws secured to the open edge of the pouch and defining the mouth thereof, and a sound producing device including a hollow normally distended flexible body provided with a rigid sound tube protruding therefrom, the said body being secured to the inner surface of one of the side walls of the pouch with the sound tube disposed parallel with and adjacent to the frame jaws thereof and adapted to be actuated by compression of either of the side walls of the pouch 15 to cause the functioning of the sound producing device.
- 15 2. A child's hand bag including a pouch formed with flexible side walls, a lining, a pair of rigid pivotally connected frame jaws secured to the

open edge of the pouch and defining the mouth thereof, and a sound producing device including a hollow normally distended flexible body provided with a rigid sound tube protruding therefrom, the said body being secured between the lining and one of the side walls of the pouch with the sound tube disposed parallel with and adjacent to the frame jaws thereof and adapted to be actuated by compression of either of the side walls of the pouch to cause the functioning of the 10 sound producing device.

5 3. The combination of a child's hand bag having flexible side walls and a pair of rigid pivotally connected frame jaws forming the mouth thereof, of a sound producing device including a hollow normally distended flexible body having a rigid sound tube protruding therefrom and disposed parallel with and adjacent to the frame jaws, said body being secured and located between the flexible side walls of the bag, whereby inward pressure against either of the said side walls will compress the hollow body to cause the sound producing device to function.
